UNITED STATES PATENT OFFICE.

WILLIAM ROMUENDER, OF MILWAUKEE, WISCONSIN.

COMBINED DOOR AND WINDOW.

1,283,918.

Specification of Letters Patent.

Patented Nov. 5, 1918.

Application filed January 22, 1917. Serial No. 143,559.

To all whom it may concern:

Be it known that I, WILLIAM ROMUENDER, a citizen of the United States, residing at Milwaukee, in the county of Milwaukee and State of Wisconsin, have invented certain new and useful Improvements in Combined Doors and Windows, of which the following is a specification, reference being had to the accompanying drawing, 10 forming a part thereof.

The main objects of this invention are to provide an outwardly swinging door having counterweighted sliding window sashes which will form a tight closure against ingress of dust, rain, snow and cold air, which when locked from the inside cannot be opened or removed from the outside by pulling the hinge pins, which will serve both as a door and ordinary window for openings 15 upon porches, balconies or the like, which will afford ample ventilation and will facilitate cleaning the window glass and admit of the use of ordinary screens and extra outside or storm windows; to prevent sagging and facilitate opening and closing the door; to facilitate the operation of the sliding sashes; and generally to simplify and improve the construction and operation of glazed doors of this class. 20 The invention consists in the construction arrangement and combination of parts as hereinafter particularly described and pointed out in the claims.

In the accompanying drawing like characters designate the same parts in the several figures.

Figure 1 is an inside elevation of a combined door and window embodying the invention; Fig. 2 is a vertical section on the line 2—2, Fig. 1; Fig. 3 is a horizontal section on the line 3—3, Fig. 1; Fig. 4 is an inside elevation, the inside casing being omitted and parts being broken away and shown in section; Fig. 5 is an enlarged plan 40 view of the swinging frame, the weight box being shown in section; Fig. 6 is an enlarged detail view showing the arrangement of the sash pulleys on the hinged side of the door; and Fig. 7 is an enlarged sectional view of one of the sash weights. 45

The device comprises a stationary door frame, consisting of jambs 1 and 2, a top rail 3, and a downwardly and outwardly sloping sill 4, which is set in the wall of a building in the usual or any suitable manner, as shown in Figs. 2 and 3, and to which

an inside casing 5 and an outside casing 6 are nailed or attached.

An outwardly swinging or opening door and window frame, composed of stiles 7 and 8, a top rail 9 and a downwardly and outwardly inclined base or bottom rail 10, and provided with an outside casing 11 fitting into the casing 6, is connected by hinges 12 at one side with the stationary frame, 65 the members of the hinges being attached to the contiguous edges of the casings 6 and 11.

The door is formed with a window opening and provided with vertically sliding 70 counterweighted upper and lower glazed sashes 13 and 14, fitting and guided in ways formed by the usual inside and outside stops 15 and 16, and parting strips 17, attached to the stiles 7 and 8 and top rail 9. The 75 window opening may extend from the top approximately the entire length of the swinging frame, or the lower part of the door may be permanently closed by a box panel 18, the window opening terminating 80 at the bottom with a downwardly and outwardly inclined window sill 19.

The stiles 7 and 8 and the top rail 9 of the swinging frame are spaced as shown in Figs. 2 and 3, from the jambs 1 and 2 and 85 the top rail 3 of the stationary frame, to form recesses at the top and sides of the swinging frame when the door is closed, these recesses being closed on the inner and outer sides by the casings 5, 6 and 11. The 90 inner edges of the stiles 7 and 8 and top rail 9 of the swinging frame are overlapped by and abut against the inside casing 5, and the casing 11 at the lock side and top of the swinging frame, overlaps and abuts against 95 the outer edges of the jamb 1 and top rail 3 of the stationary frame, as shown in Figs. 2 and 3, when the door is closed.

A weight box 20, which may be conveniently made, as shown, of sheet metal rolled 100 or pressed into channel form, is attached to the stile on the hinge side of the swinging frame, and is adapted when the door is closed, to overlap and close the joint between the casings 6 and 11 on that side of 105 the door, as shown in Fig. 3, and a double closure with a dead air space between, is thus provided at the sides and top of the door, to effectively exclude dust, rain, snow and cold air from the room or building into 110 which the doorway opens.

Any suitable kind of lock or latch 21, is

provided for fastening the door closed, and when it is so locked or fastened, the weight box 20, which overlaps the stationary casing 6, as shown in Fig. 3, prevents unauthorized removal or opening of the door from the outside by withdrawing the pins of the hinges 12, which are exposed on the outer side of the building.

The sashes 13 and 14 are counterbalanced by weights 22, inclosed and guided in the box 20, and each connected by a cord 23 passing over pulleys 24, 25 and 26, with opposite sides of a single sash, as shown in Figs. 2, 4, 5 and 6. The pulleys 24, 25, and 26 for each sash, are arranged in the same vertical plane, the pulleys 25 and 26 projecting slightly above the top rail 9, and the pulley 24 being located in a slot in the stile 8 just below and a little farther toward the center of the door than the pulley 25.

To properly counterbalance the sashes, which vary in size and weight, adjustable weights 22 are employed, each weight consisting as shown in Fig. 7, of a shell or receptacle 27, which may be conveniently made of sheet metal and filled to a greater or less extent as required, with scrap metal or other loose, heavy material.

The shells or receptacles are provided at the top with eyes or bails 28, through which the sash cords 23 are looped, and they are preferably made of square cross section to prevent their turning in the weight box and twisting the cord. The weight box 35 is provided, as shown in Fig. 3, with a vertical partition 29, to prevent interference of the weights with each other.

To prevent the swinging frame from sagging or settling and thus interfering with the proper operation of the sashes and the opening and closing of the door, the base or bottom rail 10, is provided with a roller 30, which works with a metal wear plate 31 let into the sill 4, as shown in Figs. 2 and 4.

The construction as herein shown and described, provides for the application of a screen and storm window to the window opening in the usual way, a rabbet or recess being formed by the outside casing 11 and stops 16, for the reception of the screen frame and storm sash.

The frames of the combined door and window, including the outside casings 6 and 11, are designed to be made complete and fitted with sashes in a factory, ready for installation in a building, the inside casing 5 being added according to the interior finish of the

building after the main or stationary frame is set in position.

I claim:

1. A combined door and window comprising a stationary frame having an outside casing, an outwardly swinging frame fitting into and hinged at one side to the stationary frame and having an outside casing fitting into the outside casing of the stationary frame, and a weight box attached to the hinge stile of the swinging frame and adapted to close over the joint between the outside casings of said frames. 60

2. A combined door and window comprising a stationary frame having outside and inside casings; an outwardly swinging frame fitting into and hinged at one side to the stationary frame and adapted to close 70 against the inside casing; a casing attached to the swinging frame, fitting into the outside casing of the stationary frame and overlapping the lock jamb and top rail of the stationary frame; and a weight box attached to the hinge stile of the swinging frame and adapted to close into a recess between the inside and outside casings over the joint between the outside casings. 75

3. A combined door and window comprising a stationary frame, an outwardly swinging frame hinged at one side to the stationary frame and spaced therefrom when closed at the sides and top, outside casings attached to said frames and adapted to close the space 90 between them on the outer side when the door is closed, sliding sashes fitted and guided in the swinging frame, which is provided adjacent to the top of the hinge side with two sash pulleys one above the other and on the opposite side with a single sash pulley all in the same vertical plane for a single sash, a weight box attached to the hinge stile of the swinging frame and adapted to close into the space between the inside and outside casing over the joint between the outside casings on that side of the door, the swinging frame closing inwardly against and overlapping the inside casing of the stationary frame and the outside casing of the swinging frame closing against and overlapping the lock jamb and top rail of the stationary frame, and weights 95

inclosed and guided in said box and each connected by a cord passing over one set of pulleys and across the top of the swinging frame, with opposite sides of a single sash. 100
